Patented Nov. 3, 1959

186,502

SPACE DIVIDER

Herbert Bayer, Aspen, Colo.

Application November 19, 1958, Serial No. 53,430

Term of patent 14 years

(Cl. D13—1)

Figure 1 is a perspective view of a space divider embodying my new design with the panels in open position, the rear of each panel being substantially plain;

Figure 2 is a front elevational view on a reduced scale with the panels in the closed position; and

Figure 3 is a right end view thereof.

The panel elements are shaded to show contrast.

I claim:

The ornamental design for a space divider, as shown and described.
